UNITED STATES PATENT OFFICE.

BENNO B. LEUSTIG, OF CLEVELAND, OHIO.

FLEXIBLE METAL CASING FOR LAMINATED SPRINGS.

1,240,350.

Specification of Letters Patent. Patented Sept. 18, 1917.

Application filed June 7, 1917. Serial No. 173,265.

To all whom it may concern:

Be it known that I, BENNO B. LEUSTIG, a citizen of the United States of America, residing at Cleveland, in the county of 5 Cuyahoga and State of Ohio, have invented certain new and useful Improvements in Flexible Metal Casings for Laminated Springs; and I hereby declare the following to be a full, clear, and exact description 10 of the invention, such as will enable others skilled in the art to which it pertains to make and use the same.

This invention relates to improvements in protective and lubricating flexible metal 15 casings for laminated springs, and pertains more especially to a flexible metal casing extending longitudinally and from end to end of a semi-elliptical laminated spring and serving as a covering for the top, sides 20 and bottom of the spring.

One object of this invention is to produce a casing of the character indicated which is especially adapted for use as an inclosure for a semi-elliptical laminated spring.

25 Another object is to inexpensively reinforce the casing at points spaced longitudinally of the spring.

Another object is to increase the lubricant-holding capacity of the casing and to 30 facilitate adequate lubrication of the leaves of the spring.

With these objects in view, and to the end of attaining any other object hereinafter appearing, this invention consists in certain 35 features of construction, and combinations and relative arrangement of parts, herein-after described in this specification, pointed out in the claims, and illustrated in the accompanying drawings.

40 In said drawings, Figure 1 is a side elevation of my improved casing applied to a semi-elliptical laminated spring. Fig. 2 is a side view, partly in section, of a portion of said spring and casing. Fig. 3 is a longitudinal section taken along the line 3—3, Fig. 2. Fig. 4 is a transverse section taken along the line 4—4, Fig. 2. Fig. 5 is a transverse section taken along the line 5—5, Fig. 2. Fig. 6 is a side view, largely in 45 section, of an end-portion of said spring and casing. Fig. 7 is a transverse section taken along the line 7—7, Fig. 6.

50 Referring to said drawings, 12 indicates the uppermost leaf of a semi-elliptical laminated spring, and 13 indicates the remain-

ing leaves of the spring. The uppermost leaf 13 terminates at each end in a tubular member 14 forming a head on the spring and arranged horizontally and transversely of the spring, and preferably the spring is 60 adapted to be attached at its heads 14 to a vehicle-body or other object which is to be mounted on the spring. The spring is reduced in size vertically in the direction of each end or head of the spring, and the upper 65 of adjacent leaves of the spring projects at each end of the spring in the usual manner outwardly beyond the adjacent end of the lower of said leaves.

My improved casing extends longitudinally of the spring and comprises two flexible sheet-metal strips A and B arranged to form a covering for the bottom and top respectively of the spring. Said strips extend longitudinally and from end to end 75 and from side to side of the spring.

The strip A shown covering the bottom of the spring is provided at each side of the spring with upwardly projecting flanges a spaced longitudinally of the spring. The strip B shown covering the top of the spring is provided at each side of the spring with downwardly projecting flanges b spaced longitudinally of the spring. The flanges a 80 and b of the strips A and B are arranged to 35 form a covering for the sides of the spring, and preferably each strip has its flanges adjacent one side of the spring alternating with its flanges adjacent the other side of the spring. The downwardly projecting 90 flanges b of the strip B cover the spaces between the flanges of the strip A. Preferably the space between adjacent flanges a 95 of the strip A and the outer sides of adjacent portions of said flanges are covered by a flange b of the strip B.

The strip B is provided intermediately of the side edges of each flange of its downwardly projecting flanges b with an outwardly bulging reinforcing portion 15 100 which is spaced upwardly from the lower extremity of said flange and extends up and down said flanges and to the upper end of said flange and thence inwardly from said flange over the top of the spring and forms a lubricant-receiving chamber 16 which is arranged at the inner side of said flange 105 and extends over the top of the spring. It will be observed therefore that the strip B is provided adjacent each side of the spring 110.

with outwardly bulging reinforcing portions spaced longitudinally of the strip, and preferably the outwardly bulging portions 15 adjacent one side of the spring alternate 5 with the outwardly bulging portions 15 adjacent the other side of the spring. Obviously, therefore, lubricant-receiving chambers 16 are formed adjacent each side of the spring at the inner side of the top strip B, 10 and said chambers are spaced longitudinally of the spring, and the lubricant-receiving chambers 16 adjacent one side of the spring alternate with the lubricant-receiving chambers 16 adjacent the other side of the spring. 15 The reinforcing portion 15 of each flange *b* is preferably gradually reduced in width toward its lower extremity. To facilitate distribution of lubricant to different portions of the spring and to reinforce the casing formed by the strips A and B each outwardly bulging reinforcing portion 15 of each flange *b* of the strip B and the lubricant-receiving chamber 16 formed thereby are arranged opposite the space formed between two adjacent flanges *a* of the strip A, as shown in Fig. 3.

On the casing formed by the strips A and B, adjacent each head 14 of the spring (see Figs. 1, 6 and 7), is loosely mounted a sleeve 30 consisting of opposite end-portions D and *d* of a flexible sheet-metal strip having its central portion 17 extending circumferentially of the adjacent head 14 of the spring. The sections D and *d* of each sleeve are oppositely arranged and serve as a covering for the adjacent end of the casing formed by the strips A and B. The bottom section D of each sleeve extends transversely of the bottom and from side to side of the casing 40 formed by the strips A and B and is provided at each side and externally of said casing with an upwardly projecting flange 18, and the top section *d* of said sleeve extends transversely of the top and from side to side 45 of said casing and is provided at each side and externally of said casing with a downwardly projecting flange 19 overlapping the outer side of the adjacent flange 18 of the bottom section of said sleeve.

50 Means for preventing separation of the sections D and *d* of each sleeve comprise a bolt E resting on and arranged transversely of the top sleeve-section *d* and extending through the end members *g* and *g* of a substantially U-shaped metal strap which has its central member G engaging and extending transversely of the under side of the bottom sleeve-section D, and said strap has its central member G connected with each end member *g* by an outwardly bowed resilient member 21, and the resilient members 21 of said strap act to retain said central member G and the aforesaid bolt in their sleeve-engaging position, but obviously said resilient members permit a limited movement of the

sleeve-sections in the direction required to enlarge the space vertically between the sleeve-sections as desired to avoid interference with the flexibility of the sleeve, the spring and the casing composed of the strips A and B.

Means for normally holding the strips A and B in place relative to the spring, between the head ends 14 of the spring, comprise not only the sections D and *d* of each 75 sleeve and the hereinbefore mentioned bolt E and strap or means for normally holding said sleeve-sections together, but also comprise several bolts H spaced endwise of the casing between the sleeves. Each bolt H (see 80 Fig. 5) rests on and is arranged transversely of the top strip B and is connected to and extends through the end members *l* and *l* of a substantially U-shaped metal strap which has its central member L engaging and extending transversely of the under side of the bottom strip A. The central member L of the last-mentioned strap is connected with each end member *l* of the strap by an outwardly bowed resilient member 23, and the 90 resilient members 23 of said strap act to retain said central member and the connected bolt H in their casing-engaging position, but obviously said resilient members 23 permit a limited outward movement of the strips A 95 and B as desired to avoid interference with the desired flexibility of the spring and the casing composed of said strips. Preferably said central member L of the last-mentioned strap is soldered or otherwise secured, between the resilient portions 23 of said strap, to the bottom strip A.

My improved casing is preferably provided, adjacent the inner end of each sleeve comprising sections D and *d* as hereinbefore 105 described, with a nipple R soldered or otherwise attached to the bottom strip A of the casing preferably at a point between the adjacent ends of two superimposed leaves 13 of the spring, as shown in Fig. 6, and communicating, through a hole 24 formed in said strip, with the interior of said casing, and said nipple is shown closed at its outer end by a cap *r* removably applied to the nipple in any approved manner, and obviously upon removing said cap a lubricant-supply pump or device (not shown) can be attached to the nipple for supplying lubricant, through the nipple and registering hole 24, to the spring internally of said casing. 110

I would also remark that not only are the leaves of the spring lubricated preferably before the application of my improved casing to the spring, but the lubricant-receiving chambers 16 formed internally of the 125 outwardly bulging portions 15 of the top strip B of said casing are preferably supplied with grease or viscous lubricant preparatory to the assemblage of the parts, and obviously by the construction and relative 130

arrangement of parts hereinbefore described lubricant can work its way from said chambers through the spaces between the flanges *a* of the bottom strip *A* to the leaves of the 5 spring.

What I claim is—

1. The combination, with a laminated spring, of a flexible strip forming a covering for the bottom of the spring and extending longitudinally and from side to side of the spring and provided at each side of the spring with upwardly projecting flanges spaced longitudinally of the spring, and a flexible sheet-metal strip forming a covering 10 for the top of the spring and extending longitudinally and from side to side of the spring, the flanges of the strips being arranged to form a covering for the sides of the spring, and the second-mentioned strip 15 having outwardly bulging reinforcing portions spaced longitudinally of the strip.

2. The combination with a laminated spring, of a flexible sheet-metal strip forming a covering for the bottom of the spring and extending longitudinally and from side to side of the spring and provided at each side of the spring with upwardly projecting flanges spaced longitudinally of the spring, and a flexible sheet-metal strip forming a 20 covering for the top of the spring and extending longitudinally and from side to side of the spring and provided at each side of the spring with downwardly projecting flanges spaced longitudinally of the spring, 25 the flanges of the strips being arranged to form a covering for the sides of the spring, and the second-mentioned strip having outwardly bulging portions spaced longitudinally of the strip and forming 30 lubricant-receiving chambers at the inner side 35 of said strip.

3. The combination, with a laminated spring, of a flexible sheet-metal strip forming a covering for the bottom of the spring and extending longitudinally and from side to side of the spring and provided at each side of the spring with upwardly projecting flanges spaced longitudinally of the spring, and a flexible sheet-metal strip forming a covering for the top of the spring and extending longitudinally and from side to side of the spring and provided at each side of the spring with downwardly projecting flanges spaced longitudinally of the spring, 45 the flanges of the strips being arranged to form a covering for the sides of the spring, and the second-mentioned strip being provided adjacent each side of the spring with outwardly bulging portions spaced longitudinally of the strip, and the outwardly bulging 50 portions adjacent one side of the spring alternating with the outwardly bulging portions adjacent the other side of the spring.

4. The combination, with a laminated spring, of a flexible sheet-metal strip form-

ing a covering for the bottom of the spring and extending longitudinally and from side to side of the spring and provided at each side of the spring with upwardly projecting flanges spaced longitudinally of the 50 spring, and a flexible sheet-metal strip forming a covering for the top of the spring and extending longitudinally and from side to side of the spring and provided at each side of the spring with downwardly projecting flanges spaced longitudinally of the 55 spring, the flanges of the strips being arranged to form a covering for the sides of the spring, there being lubricant-receiving chambers formed adjacent each side of the 60 spring at the inner side of the second-mentioned strip, and said chambers being spaced longitudinally of the spring.

5. The combination, with a laminated spring, of a flexible strip forming a covering for the bottom of the spring and extending longitudinally and from side to side of the spring and provided at each side of the spring with upwardly projecting flanges spaced longitudinally of the spring, 65 and a flexible strip forming a covering for the top of the spring and extending longitudinally and from side to side of the spring and provided at each side of the spring with downwardly projecting flanges spaced 70 longitudinally of the spring, the flanges of the strips being arranged to form a covering for the sides of the spring, there being lubricant-receiving chambers formed adjacent each side of the 75 spring at the inner side of the second-mentioned strip, and said chambers being spaced 80 longitudinally of the spring.

5. The combination, with a laminated spring, of a flexible strip forming a covering for the bottom of the spring and extending longitudinally and from side to side of the spring and provided at each side of the spring with upwardly projecting flanges spaced longitudinally of the spring, 85 and a flexible strip forming a covering for the top of the spring and extending longitudinally and from side to side of the spring and provided at each side of the spring with downwardly projecting flanges spaced 90 longitudinally of the spring, the flanges of the strips being arranged to form a covering for the sides of the spring, there being lubricant-receiving chambers formed adjacent each side of the 95 spring at the inner side of the second-mentioned strip, and the lubricant-receiving chambers adjacent one side of the spring alternating with the lubricant-receiving chambers adjacent the opposite side of the spring.

6. The combination, with a laminated spring, of a flexible sheet-metal strip forming a covering for the bottom of the spring and extending longitudinally and from side to side of the spring and provided at each side of the spring with upwardly projecting flanges spaced longitudinally of the spring, and a flexible sheet-metal strip forming a covering for the top of the spring and extending longitudinally and from side to side of the spring and provided at each side of the spring with downwardly projecting flanges spaced longitudinally of the spring, the flanges of the strips being arranged to form a covering for the sides of the 100 spring, each strip having its flanges at each side of the spring alternating with the adjacent flanges of the other strip, and each strip having its flanges at one side of the spring alternating with its flanges at 105 the other side of the spring.

7. The combination, with a laminated spring, of a flexible sheet-metal strip forming a covering for the bottom of the spring and extending longitudinally and from side 110

115

120

125

130

to side of the spring and provided at each side of the spring with upwardly projecting flanges spaced longitudinally of the spring, and a flexible sheet-metal strip forming a covering for the top of the spring and extending longitudinally and from side to side of the spring and provided with downwardly projecting flanges which cover the spaces between the flanges of the first-mentioned strip and have outwardly bulging portions.

8. The combination, with a laminated spring, of a flexible sheet-metal strip forming a covering for the bottom of the spring and extending longitudinally and from side to side of the spring and provided at each side of the spring with upwardly projecting flanges spaced longitudinally of the spring, and a flexible sheet-metal strip forming a covering for the top of the spring and extending longitudinally and from side to side of the spring and provided with downwardly projecting flanges which cover the space between the flanges of the first-mentioned strip and have outwardly bulging reinforcing portions extending to the upper ends of the flanges and participating in the formation of lubricant-receiving chambers extending over the top of the spring.

9. The combination, with a laminated spring, of a flexible sheet-metal strip forming a covering for the bottom of the spring and extending longitudinally and from side to side of the spring and provided at each side of the spring with upwardly projecting flanges spaced longitudinally of the spring, and a flexible sheet-metal strip forming a covering for the top of the spring and extending longitudinally and from side to side of the spring and provided with downwardly projecting flanges which are arranged to cover the spaces between the flanges of the first-mentioned strip and have outwardly bulging reinforcing portions extending to the upper ends of said flanges of the second-mentioned strip and reduced in width toward their lower extremities.

10. The combination, with a laminated spring, of a flexible sheet-metal strip forming a covering for the bottom of the spring and extending longitudinally and from side to side of the spring and provided at each side of the spring with upwardly projecting flanges spaced longitudinally of the spring, and a flexible sheet-metal strip forming a covering for the top of the spring and extending longitudinally and from side to side of the spring and provided with downwardly projecting flanges which are arranged to cover the spaces between the flanges of the first-mentioned strip, and each flange of said downwardly projecting flanges having an outwardly bulging reinforcing portion which extends up and down said flange between the side edges of the

flange and is spaced from said edges and from the lower extremity of said flange.

11. The combination, with a laminated spring, of a flexible sheet-metal strip forming a covering for the bottom of the spring and extending longitudinally and from side to side of the spring and provided at each side of the spring with upwardly projecting flanges spaced longitudinally of the spring, and a flexible sheet-metal strip forming a covering for the top of the spring and extending longitudinally and from side to side of the spring and having downwardly projecting flanges which are spaced longitudinally of the spring and arranged to overlap the sides of and to cover the spaces between the flanges of the first-mentioned strip, each flange of said downwardly projecting flanges having an outwardly bulging portion arranged to form a chamber opposite the space between adjacent flanges of the first-mentioned strip.

12. The combination, with a laminated spring, of a flexible sheet-metal strip forming a cover for the bottom of the spring and extending longitudinally and from side to side of the spring and provided at each side of the spring with upwardly projecting flanges spaced longitudinally of the spring, and a flexible sheet-metal strip forming a covering for the top of the spring and extending longitudinally and from side to side of the spring and having downwardly projecting flanges which are spaced longitudinally of the spring and arranged to cover the spaces between the flanges of the first-mentioned strip, the second-mentioned strip being provided between the side edges of each of said downwardly projecting flanges with an outwardly projecting reinforcing portion extending from said flange over the top of the spring.

13. The combination, with a laminated spring, of a flexible sheet-metal strip forming a covering for the bottom of the spring and extending longitudinally and from side to side of the spring and provided at each side of the spring with upwardly projecting flanges spaced longitudinally of the spring, and a flexible sheet-metal strip forming a covering for the top of the spring and extending longitudinally and from side to side of the spring and having downwardly projecting flanges which are spaced longitudinally of the spring and arranged to cover the spaces between the flanges of the first-mentioned strip, the second-mentioned strip being provided between the side edges of each of said downwardly projecting flanges with an outwardly bulging portion which extends over the spring, and the outwardly bulging portions of said downwardly projecting flanges forming chambers which are arranged at the inner sides of said flanges and extend over the spring.

14. The combination, with a laminated spring, of a flexible sheet-metal strip forming a covering for the bottom of the spring and extending longitudinally and from side to side of the spring and provided at each side of the spring with upwardly projecting flanges spaced longitudinally of the spring, and a flexible sheet-metal strip forming a covering for the top of the spring and 10 extending longitudinally and from side to side of the spring and provided at each side of the spring with downwardly projecting flanges spaced longitudinally of the spring, each strip having its flanges adjacent one 15 side of the spring alternating with its flanges adjacent the opposite side of the spring, the space between adjacent flanges of the first-mentioned strip and the outer sides of adjacent portions of said flanges 20 of said first-mentioned strip at each side of the spring being covered by a flange of the second-mentioned strip, said second-mentioned strip being provided at each side of the spring with outwardly projecting reinforcing portions, and the reinforcing portions adjacent one side of the spring al- 25 ternating with the reinforcing portions adjacent the other side of the spring.
15. The combination, with a semi-elliptical laminated spring having one of its leaves 30 projecting beyond the other leaves of the spring at each end of the spring and terminating in heads, of a casing comprising flexible metal strips extending longitudinally of the spring and into proximity to 35 the aforesaid heads and forming a covering for the top, sides and bottom of the spring, and flexible members embracing the aforesaid heads and connected to the said casing, the casing being provided between the central portion of the spring and said head-embracing members with inlets at which lubricant may be supplied to the interior of 40 said casing.
- In testimony whereof, I sign the foregoing specification, in the presence of two 45 witnesses.
